LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

WATER-HEATING APPARATUS.

1,258,394.

Specification of Letters Patent.

Patented Mar. 5, 1918.

Application filed May 7, 1915. Serial No. 26,528.

To all whom it may concern:

Be it known that I, LEE S. CHADWICK, a citizen of the United States, residing at East Cleveland, in the county of Cuyahoga and State of Ohio, have invented a certain new and useful Improvement in Water-Heating Apparatus, of which the following is a full, clear, and exact description, reference being had to the accompanying drawings.

10 This invention relates to water heaters of the sort comprising a water storage and circulating apparatus, in combination with a suitable heating device. The apparatus disclosed herein is especially designed for use 15 with liquid fuel burners, the invention including novel means of supporting said burner in correct operative relation to the storage and circulating apparatus.

The embodiment of my invention which 20 includes a liquid fuel burner is, therefore, especially suitable for use in homes, barbershops, and other places where hot water is desired, and that have not the conveniences of gas and water supply systems; although 25 I would not make the impression that the water storage and circulating apparatus is not equally well adapted for employment with gas stoves, coal stoves, electric heating elements, etc., in the production of an efficient water heater.

The objects of the invention are to provide an apparatus of the aforesaid character that is prompt and efficient in the heating of water; that is simple of construction, and 35 very convenient of use; that will automatically deliver the hottest water to the vicinity of a faucet through which it may be withdrawn; wherein a natural circulation prevails during the time that the heating device 40 is in operation; and that will maintain the temperature of the water contained therein at a high degree for a comparatively long time after the activity of the heating device has been stopped or suspended.

45 A further object of the invention is to incorporate within the water heating apparatus, a steamer that may be used in homes for performing certain cooking operations, and in barbershops, massage parlors, and 50 such places, for steaming hot towels and the like.

The structural details whereon the foregoing objects are dependent for their fulfillment will be pointed out during the course 55 of the following description.

In the accompanying drawings which form a part hereof, Figure 1 is a front elevation of the water heater of my invention; Fig. 2 is a horizontal plan on line 2—2 of Fig. 1; Fig. 3 is a vertical section through the lower portion of the heating device and the supporting structure therefor, the plane of section being indicated by the line 3—3 of Fig. 2; Fig. 4 is an enlarged detail on line 4—4 of Fig. 1; Fig. 5 is a central vertical section through the upper portion of the water heater on line 5—5 of Fig. 1; Fig. 6 is a plan view of the water heater with the cover of the reservoir removed; Fig. 7 is a horizontal section through the apparatus on the lines 7—7 of Figs. 1 and 5, and looking upward as indicated by the arrows; Fig. 8 is a sectional detail of the valve which controls the flow of water from the reservoir to the circulating element, as represented by the line 8—8 of Fig. 5, and Fig. 9 is a perspective view of the elements of this valve in separated condition.

I will now proceed to describe the invention by the use of reference characters. 80 The water storage and circulating apparatus A is supported upon a stand B, and a liquid fuel heater C is sustained in operative relation to the storage and circulating apparatus, by a shelf of the stand B.

The aforesaid stand B comprises a ring 1 to which are connected the upper ends of legs 2, said legs being of angle formation (as shown in Fig. 2) throughout their lengths except at their tops where they 90 are spread out and curved to correspond to the curvature of the ring 1. Here they are riveted to said ring, the legs being spaced about the circumference of said ring at substantially 90° apart, and between each leg 95 and the ring is confined the vertical flange of an angle bracket 5. The horizontal flanges of the brackets 5 project inward to form supports for the water storage and circulating apparatus. At a suitable distance below the ring 1, a shelf 6 is supported by the legs 2, the shelf in the present embodiment of my invention being square and having its corners confined within the angles of the legs and held there by rivets 100 7. The shelf 6 has a peripheral flange 8 along each side, through which the rivets 7 extend, and the top of the shelf is gradually inclined upward from its lateral edges 105 toward the center, but at equal distances 110

- on each side of the center the material of the shelf is turned abruptly downward and then into a horizontal portion 10. The shelf is formed from its rear edge to the center 5 in substantially the same manner as that just described, and as shown in Fig. 3, but the forward, central portion of the shelf is inclined gradually downward from its edge to the plane of the portion 10, as will 10 also be observed from said Fig. 3. The center of the portion 10 is provided with a depression 11, for the obvious purpose of collecting any liquid which may drip from the heating device.
- 15 I employ, as the heating device, a liquid fuel heater, comprising a liquid fuel reservoir 12, within the central portion of which is a tubular burner 13, and a flue or drum 14, that is supported above the burner 13.
- 20 To adapt this heater to its present use, I attach to the bottom of the reservoir, a shoe 15 that consists of a strip of metal that is bent into a rectangular shape as shown in Fig. 2, and that has its upper edge soldered, 25 or otherwise secured, to the reservoir 12. The rear ends of the side portions of the shoe converge toward the rear to facilitate the insertion of the shoe within the guide formed by the vertical walls 9 of the de-
- 30 pressed, central portion of the shelf 6. A handle 16 is secured to the front of the reservoir, and a bail 17, to the upper surface of the rear portion thereof, the bail being slightly to one side of a point diametrically 35 opposite the handle 16 to enable the user to grasp it after the heater has been partly withdrawn from the shelf, without peril of engaging his arm with the drum. As will be observed, the front side of the shoe 15 is 40 left open to supply air to the bottom of the tubular burner 13.
- The water storage and circulating apparatus will now be described. 20 represents a cylindrical shell or drum that has its upper and lower edges wired at 21 and 22 respectively, and a short distance below its upper edge the same is provided with a series of embossed beads 23, for imparting strength to the drum and improving its appearance.
- 45 Spaced a suitable distance above the lower edge of the drum, there is an inwardly extending ridge 24, and immediately above this ridge the drum is provided with a series of openings 25. An inner drum 26 is 50 arranged to be slipped down through the top of the outer drum until its outwardly flared lower end 27 engages the top of the ridge 24, which forms a support for said drum. It will be observed from Fig. 5 that 55 the upper end of the inner drum is spaced some distance below the corresponding end of the outer drum, and is retained at a fixed distance radially therefrom by spacers 28, that are Z shaped in cross section, one 60 flange whereof is attached to the inner drum,

and the other of which engages the inner surface of the outer drum, above the beads 23. This construction may be better understood from an inspection of the broken away portion of Fig. 6.

The reservoir 30 is cylindrical and of a diameter somewhat less than the diameter of the inner shell 26, the space between the reservoir and said shell being shown as substantially the same as that between the inner 70 and outer shells. The upper end of the reservoir is flared outward and is inclined upward, as shown at 31, to a diameter substantially equal to the inside diameter of the outer shell, the wall of the reservoir then 75 being turned upward and wired at 32. The upper ends of the spacers 28 are inclined at substantially the same angle as the portion 31 of the reservoir, and said portion may rest upon the spacers for the purpose of supporting the reservoir within the shells; or 80 the reservoir may depend for its support upon the engagement of its wired upper end 32 with the wired end 21 of the outer shell. A cover 33 is adapted to close the upper end 85 of the reservoir, and its peripheral, depending flange 34 fits down within the enlarged portion of the reservoir. The bottom 35 of the reservoir constitutes a shallow inverted cone. Within the apex of the cone is secured 90 a dished plate 36 having a central vertical tubular neck 37 for the reception of a correspondingly shaped neck 38 of a valve cup 39, the bottom whereof is perforated, as shown at 40 in Figs. 5 and 8. The neck 38 of the valve cup may have a forced fit within the neck 37 of the plate 36, in which case the necks may be secured together by soldering; or the necks may be threaded so 95 that the valve cup can be easily removed. A valve disk 41 occupies the cup 39, and the same has a central aperture 42, that registers with the neck 38 of the cup, and a series of peripheral lugs 43 which centralize the disk within the cup. The cup is closed 100 by a cover 44 that is shown as having a pressed fit down over the sides of the cup, although the same might be screwed onto the cup. A fitting 50 is applied to the outside of the bottom 35, and has a flange 51 105 that corresponds in shape to the dished plate 36 and occupies a position directly beneath said plate. A transverse hollow boss 52 occupies the center of the fitting, and one end 110 of the boss has an aperture that is flanged inward for the reception of the end of a pipe which constitutes the circulating element 53 of the apparatus. This element is formed in a spiral, and the successive convolutions thereof gradually progress upward at about the same angle as the inclination of the bottom 35. Finally, the pipe 115 is led across to one side of the reservoir and passed upward between its cylindrical wall and the inner shell 26 to where it is passed 120

125

130

through the portion 31 of the reservoir and is then turned downward over and in proximity to the wall of the reservoir. The circulating element terminates, at its upper 5 end, within a compartment or chamber designated D, that is divided from the reservoir proper by a partition 55 formed of a pair of substantially parallel, spaced walls that extend across the reservoir, a little for- 10 ward of its center, and have vertical ends which are secured to the wall of the reservoir, and a curved edge which is joined to the reservoir wall between the points of its vertical connection therewith. The spaced 15 walls of the partition produce an air space which very effectually insulates the compartment D from the storage reservoir. This compartment is adapted to be closed by a cover 56 that may entirely or partially 20 cover the compartment, in the latter instance, the cover being permanently attached, if desired, and constituting a shield to prevent hot water from splashing as it is discharged from the circulating element. 25 A steamer or towel tray 57, having a perforated bottom, is supported within the remaining portion of the upper end of the reservoir by having its outwardly flared upper end 58 resting upon the portion 31. 30 A faucet 60 has connection with the interior of the compartment D, through the cylindrical wall of the reservoir, and a box shaped casing 61 is secured to said reservoir wall about the shank of the faucet and ex- 35 tends upward to the portion 31. The front surface of the casing 61 is in the plane of the enlarged, cylindrical upper end of the reservoir, for a purpose which will be apparent from the following. It is obvious that the 40 outer and inner shells have to be notched from their upper edges downward, as shown at 63 and 64, respectively, for the purpose of allowing the faucet to pass downward to its final position as the reservoir is lowered into 45 the shells. The front wall of the casing 61, therefore, closes the notch 63 in the outer shell, when the parts are assembled, and in condition for use.

While access to the interior of the storage 50 reservoir may be easily gained by the removal of the cover 33, as for the purpose of dipping water therefrom, in the event that the steamer occupies the upper end of the reservoir, this operation will be somewhat 55 interfered with. Especially in barbershops and such places, where the steamer or towel tray is almost continually in use, it is an advantage to have a faucet through which the water within the storage reservoir may be 60 withdrawn, and such a faucet is shown at 65. The shank of the faucet is threaded into a boss 66 of a fitting 67 that is preferably formed of a casting having its flanged end riveted or otherwise secured to the cylindri- 65 cal wall of the reservoir, said wall having

an opening 68 through which the faucet communicates with the reservoir. This construction enables the apparatus to be disassembled very conveniently by simply removing the faucet from the fitting 67. 70

In the operation of the device, the products of combustion from the heater C rise in direct contact with the bottom of the reservoir and with the circulating element 53. Passing about the bottom, said products continue their upward course between the wall of the reservoir and the inner shell 26. The fact that the openings 25 in the outer shell are spaced a substantial distance above the top of the heater drum, causes a downward 75 draft to be created in the space between the inner and outer shells so that the products of combustion are drawn over the top of the inner shell and down through such space and are exhausted through the openings 25. 80 It is obvious, therefore, that the products of combustion are caused to exercise their highest efficiency in the heating of the circulating element, the bottom of the reservoir, and the cylindrical wall thereof in their upward 85 course, and that they are protected from the cooling influence of the atmosphere by the descending products through the space between the outer and inner shells. 90

Assuming that the water level within the 95 reservoir is slightly below the bottom of the steamer 57, the weight of the water will elevate the valve disk 41 and allow the water to flow through the openings 40, the neck 38 of the valve cup, the fitting 50, and accumulate 100 within the circulating element to a level substantially equal to the level of the water within the reservoir. As the temperature of the water within the circulating element rises, and the air within the water expands, 105 the water will be forced upward and may overflow through the downturned upper end of the element into the compartment D. If the expansion within the element is not sufficient to accomplish this end, the water will 110 actually be forced through the aforesaid course and discharge into the compartment D, upon the generation of steam within the circulating element. The pressure thus created within the element may hold the valve 115 disk upon the bottom of the cup 39 until a quantity of water has been removed from the element, when the pressure therein will fall to less than the weight of the water within the reservoir, when it will act to open 120 the valve and water will flow into the circulating element. This operation continues as long as the heater is active, constantly delivering the hottest water into the compartment D where it may be drawn off through 125 the faucet 60. If the water is not used out of the compartment D as fast as it accumulates therein, it will simply overflow into the reservoir and assist in heating the water contained therein. This overflow is permit- 130

ted by the ends of the cover 56 being cut away as shown at 70, in Fig. 6. The fact that the wall of the reservoir is spaced some distance from the outer shell 20 and the 5 space between is divided by the inner shell 26, very effectually protects the reservoir from the effect of the atmospheric temperature, so that the temperature of the water within the reservoir, even after the heater 10 has ceased to act, is retained at a high degree for a considerable time.

Attention is also called to the fact that the small quantity of water contained at one time within the circulating element, the 15 thinness of the wall of said element, and the directness of contact of the products of combustion with the element, contribute toward a very prompt heating of a small quantity of water and the delivery of it to the compartment D, for use almost immediately after the lighting of the heater; and the isolation of said compartment, through the dead air space afforded by the double wall partition 55, from the cool water within the reservoir, 20 protects it from being affected thereby.

I have already stated that the water storage and circulating apparatus of the water heater disclosed herein may be used in connection with various heating devices, so that 30 this part of my invention may constitute an article of manufacture and sale, entirely independent of the particular form of heating device which is shown herein. Therefore, certain of the following claims are directed 35 to the storage and circulating apparatus alone.

Having thus described my invention, what I claim is:—

1. An apparatus of the character set forth 40 comprising a reservoir, a circulating element communicatively connected to the reservoir, a valve for controlling the flow of water from the reservoir to the circulating element, said valve being operative when the 45 weight of water within the reservoir overbalances the pressure within said element, and a chamber into which the circulating element discharges, said chamber being arranged, when the water within it has 50 reached a predetermined level, to overflow into the reservoir, the circulating element being arranged for subjection to the influence of a heating device.

2. An apparatus of the character set forth 55 comprising an outer shell, an inner shell spaced therefrom, a reservoir reposing within and spaced from said inner shell, the space between the upper ends of the outer shell and the reservoir being closed above 60 the upper edge of the inner shell, there being a passageway provided adjacent the upper edge of the inner shell through which the spaces on its opposite sides communicate, the outer shell having an exhaust opening adjacent the lower end of the inner shell, and the

space between the inner and outer shells being closed at a point below the last mentioned opening, a partition dividing the reservoir into a high temperature compartment and a storage compartment, a circulating 70 element communicatively connected to the lower portion of the reservoir and arranged to discharge into the high temperature compartment, and a valve for controlling the flow of water from the storage compartment 75 into the circulating element, the circulating element being arranged for subjection to the influence of a heating device.

3. An apparatus of the character set forth comprising an outer shell, an inner shell 80 spaced therefrom, a reservoir reposing within and spaced from said inner shell, the space between the upper ends of the outer shell and the reservoir being closed above the upper edge of the inner shell, there being a passageway provided adjacent the upper edge of the inner shell through which the spaces on its opposite sides communicate, the outer shell having an exhaust opening adjacent the lower end of the inner shell, and the 85 space between the inner and outer shells being closed at a point below the last mentioned opening, a partition dividing the reservoir into a high temperature compartment and a storage compartment, a circulating 90 element communicatively connected to and reposing beneath the lower portion of the reservoir and arranged to discharge into the high temperature compartment, a valve for controlling the flow of water from the storage compartment into the circulating element, and a heating device arranged to discharge its heat into the bottom of the outer shell.

4. An apparatus of the character set forth 105 comprising an outer shell, an inner shell spaced therefrom, a reservoir reposing within and spaced from said inner shell, the upper ends of the outer shell and the reservoir meeting above the upper edge of the inner shell, there being a passageway provided adjacent the upper end of the inner shell through which the spaces on its opposite sides communicate, the outer shell having an exhaust opening adjacent the lower 110 end of the inner shell, and the inner and outer shells meeting at a point below the last mentioned opening, a partition comprising a pair of spaced walls dividing the reservoir into a high temperature compartment and a 115 storage compartment, a circulating element communicatively connected to the lower portion of the reservoir and arranged to discharge into the high temperature compartment, and a valve for controlling the flow of water from the storage compartment into the circulating element, the circulating element being arranged for subjection to the influence of a heating device.

5. An apparatus of the character set forth 130

- comprising an outer shell having an inwardly extending ledge spaced upward from its bottom, an inner shell which reposes within the outer shell and has its lower end flared outward for engagement with said ledge, the outer shell being provided with an escape opening above its ledge, a reservoir reposing within and spaced from the inner shell and having its upper end flared outward for engagement with the outer shell a distance above the upper edge of the inner shell, a partition which divides the reservoir into a high temperature and a storage compartment, a circulating element communicatively connected to the lower portion of the reservoir and reposing beneath the same, said element being arranged to discharge into the high temperature compartment, a valve for controlling the flow of water from the storage compartment into the circulating element, the circulating element being arranged for subjection to the influence of a heating device.
6. An apparatus of the character set forth comprising an outer shell having an inwardly extending ledge spaced upward from its bottom, an inner shell which reposes within the outer shell and has its lower end flared outward for engagement with the ledge of the outer shell, the outer shell being provided with an escape opening above its ledge, a reservoir reposing within and spaced from the inner shell and having its upper end flared outward for engagement with the outer shell a distance above the upper edge of the inner shell, a partition consisting of an insulating wall which divides the reservoir into a high temperature and a storage compartment, a circulating element communicatively connected to the lower portion of the reservoir and reposing beneath the same, said element being arranged to discharge into the high temperature compartment, a valve for controlling the flow of water from the storage compartment into the circulating element, the circulating element being arranged for subjection to the influence of a heating device, a removable cover for the high temperature compartment, a steamer that is arranged to be supported within the upper end of the reservoir, a closure for the upper end of the reservoir, and a faucet for the high temperature compartment.
- 55 7. An apparatus of the character set forth comprising an outer shell, an inner shell which reposes within the outer shell, the space between the shells being closed adjacent the lower end of the inner shell, the outer shell being provided with an escape opening above the lower end of the inner shell, a reservoir reposing within and spaced from the inner shell, the space between the reservoir and the outer shell being closed above the upper edge of the inner shell,
- there being a passageway provided adjacent the upper end of the inner shell through which the spaces on its opposite sides communicate, a partition which divides the reservoir into a high temperature and a storage compartment, a circulating element communicatively connected to the lower portion of the reservoir and reposing beneath the same, said element being arranged to discharge into the high temperature compartment, a valve for controlling the flow of water from the storage compartment into the circulating element, the circulating element being arranged for subjection to the influence of a heating device, and a shield extending across the high temperature compartment above the discharge end of the circulating element.
8. An apparatus of the character set forth comprising an outer shell having an inwardly extending ledge spaced upward from its bottom, an inner shell which reposes within the outer shell and has its lower end flared outward for engagement with the aforesaid ledge, the outer shell being provided with an escape opening above its ledge, a reservoir reposing within and spaced from the inner shell and having its upper end flared outward for engagement with the outer shell, there being a passageway provided adjacent the upper edge of the inner shell through which the spaces on opposite sides thereof communicate, an insulating partition which divides the reservoir into a high temperature and a storage compartment, a circulating element communicatively connected to the lower portion of the reservoir and reposing beneath the same, said element being arranged to discharge into the high temperature compartment, a valve for controlling the flow of water from the storage compartment into the circulating element, the circulating element being arranged for subjection to the influence of a heating device, a removable cover for the high temperature compartment, a steamer that is arranged to be supported within the upper end of the reservoir, a closure for the upper end of the reservoir, a faucet through which the water may be withdrawn from the high temperature compartment, and a second faucet communicatively connected to the lower portion of the reservoir.
9. An apparatus of the character set forth comprising a substantially cylindrical outer shell having an inwardly extending ledge spaced upward from the bottom thereof, a cylindrical inner shell that is adapted to be inserted through the top of the outer shell and having its lower end flared outward for engagement with the aforesaid ledge, the outer shell having an escape opening above said ledge, a reservoir that is adapted to be inserted through the upper ends of the

aforesaid shells and having its upper end flared outward for engagement with the outer shell, the upper edge of the inner shell being spaced below the outwardly flared 5 portion of the reservoir, spacers for maintaining the inner and outer shells at a fixed distance apart, a partition for dividing the reservoir into a high temperature and a storage compartment, a circulating element 10 communicatively connected to the bottom of the reservoir and reposing partially therebeneath and extending up alongside the reservoir and into the high temperature compartment, a faucet spaced downward 15 from the upper end of the reservoir and communicatively connected to the high temperature compartment, the inner and outer shells being notched downward from their upper ends to allow said faucet to pass 20 downward to its normal position, a member carried by the reservoir for closing the notch in the outer shell, a fitting communicatively connected to the reservoir near its bottom, and a faucet removably connected to said 25 fitting and extending outward through apertures within the shells.

10. An apparatus of the character set forth comprising a substantially cylindrical outer shell having an inwardly extending 30 ledge spaced upward from the bottom thereof, a cylindrical inner shell that is adapted to be inserted through the top of the outer shell and having its lower end flared outward for engagement with the aforesaid 35 ledge, the outer shell having an escape opening above said ledge, a reservoir that is adapted to be inserted through the upper ends of the aforesaid shells and having its upper end flared outward for engagement 40 with the outer shell, the upper edge of the inner shell being spaced below the outwardly flared portion of the reservoir, spacers for maintaining the inner and outer shells at a fixed distance apart, a partition 45 for dividing the reservoir into a high temperature and a storage compartment, a circulating element communicatively connected to the bottom of the reservoir and reposing partially therebeneath and extending up 50 alongside the reservoir and into the high temperature compartment, a shield partially closing the compartment above the end of said element, a faucet spaced downward from the upper end of the reservoir and 55 communicatively connected to the high temperature compartment, the inner and outer shells being notched downward from their upper ends to allow said faucet to pass downward to its normal position, and a member 60 carried by the reservoir for closing the notch in the outer shell.

11. An apparatus of the character set forth comprising a substantially cylindrical outer shell having an inwardly extending 65 ledge spaced upward from the bottom

thereof, a cylindrical inner shell that is adapted to be inserted through the top of the outer shell and having its lower end flared outward for engagement with the aforesaid ledge, the outer shell having an 70 escape opening above said ledge, a reservoir that is adapted to be inserted through the upper ends of the aforesaid shells and having its upper end flared outward for engagement with the outer shell, the upper 75 edge of the inner shell being spaced below the outwardly flared portion of the reservoir, spacers for maintaining the inner and outer shells at a fixed distance apart, a partition for dividing the reservoir into a 80 high temperature and a storage compartment, a circulating element communicatively connected to the bottom of the reservoir and reposing partially therebeneath and extending up alongside the reservoir 85 and into the high temperature compartment, a faucet spaced downward from the upper end of the reservoir and communicatively connected to the high temperature compartment, the inner and outer shells being notched downward from their upper 90 ends to allow said faucet to pass downward to its normal position, and a member carried by the reservoir for closing the notch in the outer shell.

12. An apparatus of the character set forth comprising an outer shell, an inner shell spaced therefrom, and a reservoir reposing within and spaced from said inner shell, the space between the upper ends of 100 the outer shell and the reservoir being closed above the upper edge of the inner shell, there being a passageway provided adjacent the upper edge of the inner shell through which the spaces on its opposite 105 sides communicate, the outer shell having an exhaust opening adjacent the lower end of the inner shell, and the space between the inner and outer shells being closed at a point below the last mentioned opening.

13. An apparatus of the character set forth comprising an outer shell, an inner shell spaced therefrom, and a reservoir reposing within and spaced from said inner shell, the upper ends of the outer shell and 115 the reservoir meeting above the upper edge of the inner shell, there being a passageway provided adjacent the upper end of the inner shell through which the spaces on its opposite sides communicate, the outer shell 120 having an exhaust opening adjacent the lower end of the inner shell, and the inner and outer shells meeting at a point below the last mentioned opening.

14. An apparatus of the character set 125 forth comprising an outer shell having an inwardly extending ledge spaced upward from its bottom, an inner shell which reposes within the outer shell and has its lower end flared outward for engagement 130

with said ledge, the outer shell being provided with an escape opening above its ledge, and a reservoir reposing within and spaced from the inner shell and having its 5 upper end flared outward for engagement with the outer shell a distance above the upper edge of the inner shell.

15. An apparatus of the character set forth comprising a substantially cylindrical shell having an inwardly extending ledge spaced upward from the bottom thereof, a cylindrical inner shell that is adapted to be inserted through the top of the outer shell and having its lower end flared outward for 10 engagement with the aforesaid ledge, the outer shell having an escape opening above said ledge, a reservoir that is adapted to be inserted through the upper ends of the aforesaid shells and having its upper end 15 flared outward for engagement with the outer shell, the upper edge of the inner shell being spaced below the outwardly flared portion of the reservoir, and spacers for 20 maintaining the inner and outer shells at a fixed distance apart.

25. An apparatus of the character set forth comprising an outer shell, an inner shell spaced therefrom, a reservoir reposing

within and spaced from said inner shell, a faucet carried by and spaced downward 30 from the upper end of the reservoir and extending outwardly therefrom, the inner and outer shells being notched downward from their upper ends to allow said faucet to pass downward to its normal position when 35 the reservoir is inserted through the upper ends of the shells, and a member carried by the reservoir for closing the notch in the outer shell.

17. An apparatus of the character set 40 forth comprising a reservoir, a circulating element communicatively connected to the reservoir, and a chamber into which the circulating element discharges, said chamber being arranged, when the water within it 45 has reached a predetermined level, to overflow into the reservoir, the circulating element being arranged for subjection to the influence of a heating device.

In testimony whereof, I hereunto affix my 50 signature in the presence of two witnesses.

LEE S. CHADWICK.
